UNITED STATES PATENT OFFICE.

JOHN F. HEMENWAY, OF NEW YORK, N. Y.

PRESSURE-RELEASING DEVICE FOR CLOTHES-WRINGERS.

1,220,116.

Specification of Letters Patent. Patented Mar. 20, 1917.

Application filed September 9, 1916. Serial No. 119,180.

To all whom it may concern:

Be it known that I, JOHN F. HEMENWAY, a citizen of the United States, residing at New York city, in the county of New York 5 and State of New York, have invented certain new and useful Improvements in Pressure-Releasing Devices for Clothes-Wringers, of which the following is a specification, reference being had therein to the accompanying drawing.

This invention relates to certain new and useful improvements in pressure releasing device for clothes wringers, the object being to provide simple means for releasing the 15 pressure on the pressure rolls in case of accident by providing the movably mounted top bar with an operating member which when depressed forces the releasing bars outwardly so as to move the pivoted latches out of the 20 path of the top bar in order to allow the same to move vertically.

Other and further objects and advantages of the invention will be hereinafter set forth and the novel features thereof defined by the 25 appended claims.

In the drawings,

Figure 1 is a side elevation of a clothes wringer showing the application of my improved construction of releasing mechanism 30 thereto; and

Fig. 2 is a detail perspective of the releasing mechanism detached from the wringer.

Like numerals of reference refer to like parts in the several figures of the drawing.

35 In carrying out my invention, I employ a frame formed of slotted side bars 1 connected together by cross bars 2 and provided with a movably mounted top bar 3 which is provided with wear plates 4 engaged by pivoted latches 5 for holding the top bar in predetermined position within the wringer frame. Mounted within the slotted side bars of the wringer frame are a pair of superposed pressure rolls 6 and 7 above which is 40 arranged pressure means comprising pressure springs 9 and a pressure bar 10 which is engaged by pressure screws 11 carried by the movably mounted top bar 3 for adjusting the pressure on the pressure rolls.

45 50 The pivoted latches 5 are carried by plates 12 secured to the upper end portions of the side bars 1 of the wringer frame, said plates being provided with openings 13 through which the reduced ends 14 of the releasing bars 15 extend and which are slidably

5 mounted on the under side of the top bar 3 and are provided with enlarged abutting ends having semi-conical-shaped recesses 16 adapted to receive the conical-shaped ends 17 of the shank 18 of a push button 19 which 60 is slidably mounted within a bearing sleeve 20 secured centrally within the top bar as clearly shown in Fig. 1, the lower end of the shank being provided with a head 21 for preventing the push button from becoming 65 detached from the top bar and is surrounded by a coil spring 22 for normally holding the same in raised position.

In the construction of releasing bar as herein shown, the same is slotted to receive 70 screws 23 for slidably mounting the same on the under side of the top bar 3 and is provided with slots 24 through which the pressure screws 11 pass and are free to move therein so that the releasing bars are free to 75 move outwardly when they are forced apart by the push button being forced downwardly so as to cause the conical-shaped end to move downwardly within the conical-shaped sockets formed on the abutting ends thereof 80 which forces the abutting ends apart the proper distance to cause the reduced ends 14 to move the pivoted latches 5 from off of the ends of the top bar so as to release the top bar.

85 In the operation of the releasing device as herein shown and described, assuming that the top bar is in the position in the wringer frame as shown in Fig. 1 with the latches in position to hold said top bar in predetermined position by forcing the push button downward, the releasing bars will move outwardly into engagement with the pivoted latches so as to force said latches out of the path of travel of the top bar, and as the top bar moves vertically, the pressure is released on the pressure rolls.

I claim:

1. A clothes wringer, comprising a frame having pressure rolls and pressure means for said rolls mounted therein, a movably mounted top bar having means for adjusting said pressure means, pivoted members mounted on the side bars for holding said top bar in predetermined position, releasing bars slidably mounted on the under side of said top bar, and a movably mounted member slidably mounted in said top bar extending between said releasing bars for moving said releasing bars in opposite direction for

moving said movable members out of the path of travel of said top bar for releasing the pressure on said pressure rolls.

2. A clothes wringer, comprising a frame 5 having pressure rolls and pressure means for said rolls mounted therein, a movably mounted top bar having means for adjusting said pressure means, pivoted members for holding said top bar in predetermined 10 position, releasing bars carried by said top bar having abutting ends provided with sockets, and an operating member slidably mounted in said top bar extending into said sockets for forcing said releasing bars outwardly to actuate the pivoted members to 15 release the top bar.

3. A clothes wringer, comprising a frame having pressure rolls and pressure means for said rolls mounted therein, a movably 20 mounted top bar having means for adjusting said pressure means, plates carried by the side bars of said frame, movable latches carried by said plates for holding said top bar in predetermined position, releasing bars 25 slidably mounted thereon, said releasing bars having abutting ends provided with registering sockets, and a movably mounted member mounted in said top bar having a conical end extending into the socket of said releasing bars for moving said releasing bars 30 outwardly into engagement with said movable members for releasing said top bar.

4. A clothes wringer comprising a frame having pressure rolls and pressure means 35 for said rolls mounted therein, means carried by the side bars of said frame for holding said pressure means in predetermined position, releasing bars arranged to cooperate with said retaining means for releasing 40 said pressure means, and a slidably mounted member arranged between said releasing bars and having means for forcing said releasing bars outwardly for releasing said pressure means.

45 5. A clothes wringer, comprising a frame having pressure rolls and pressure means for said rolls mounted therein, a movably mounted top bar having means for adjusting said pressure means, apertured plates 50 carried by the side bars, movable latches carried by said plates for holding said top bar in predetermined position within said frame, releasing bars slidably mounted on the under side of said top bar having abutting 55 ends provided with registering sockets, said bars being provided with reduced ends extending through the apertures of said plates in alinement with said movable members and a movably mounted member mounted in 60 said top bar having a conical end extending into the registering sockets of said releasing bars for moving said releasing bars outwardly to throw said movable members out of the path of travel of said top bar.

65 6. A clothes wringer, comprising a frame

having pressure rolls and pressure means for said rolls mounted therein, a movably mounted top bar having means for adjusting said pressure means, apertured plates secured to the side bars, pivoted latches mounted on said plates extending over said top bar, releasing bars slidably mounted on the under side of said top bar having abutting ends provided with registering notches, said bars being provided with reduced outer ends extending through the apertures of said plate in alinement with said pivoted latches, and a push button having a shank 70 slidably mounted within the top bar and provided with a conical shaped portion extending into the registering notches for forcing said releasing bars in opposite directions for moving said pivoted latches out of the path of travel of said top bar.

7. A clothes wringer comprising a frame 75 having pressure rolls and pressure means for said rolls mounted therein, pivoted latches carried by said frame for holding said pressure means in predetermined position therein, releasing bars slidably mounted 80 on said frame, and a push button mounted between said releasing bars having a conical portion for separating said bars for moving said bars into engagement with said latches, for releasing said pressure means.

8. A clothes wringer, comprising a frame 85 having pressure rolls and pressure means for said rolls mounted therein, a movably mounted top bar having means for adjusting said pressure means, apertured plates 90 carried by the side bars of said frame, latches pivotally mounted on said plates cooperating with said top bar for holding said top bar in predetermined position within said frame, slidably mounted releasing bars 95 carried by said top bar having abutting ends provided with registering notches, said releasing bars extending through the apertures of said plates in alinement with said pivoted latches, said top bar having a vertically disposed bearing, a push button provided with a shank slidably mounted in said bearing, said push button having a conical portion extending into the notches of said releasing bars for forcing said releasing 100 bars outwardly to actuate said latches, and a spring surrounding the shank of said push button above said top bar.

9. A clothes wringer, comprising a frame 105 having pressure rolls and pressure means for said rolls mounted therein, a movably mounted top bar having means for adjusting said pressure means, plates carried by the side bars of said frame, pivoted latches mounted upon said plates engaging said bar 110 for holding said top bar in predetermined position within said frame, screws carried by said top bar, slotted bars mounted upon said screws having abutting ends provided with registering notches, said bars having 115 120 125 130

reduced ends extending through said plates and into engagement with said latches, said top bar having a vertically disposed bearing, a push button having a shank mounted in 5 said bearing and provided with a conical portion extending into notches of said bars for forcing said bars apart to move said latches out of the path of travel of said top bar, the shank of said push button being 10 provided with a head at its lower end and

having a spring surrounding the same above said top bar for returning said push button into normal position.

In testimony whereof I hereunto affix my signature in the presence of two witnesses. 15

JOHN F. HEMENWAY.
